(57) **CLAIM**

The ornamental design for a fencing panel sheet, as shown and described.

DESCRIPTION

FIG. 1 is a front perspective view of a fencing panel sheet showing my new design according to a first embodiment; FIG. 2 is a front elevational view of the first embodiment; FIG. 3 is a rear elevational view of the first embodiment; FIG. 4 is a right side elevational view of the first embodiment;

FIG. 5 is a left side elevational view of the first embodiment; FIG. 6 is a top plan view of the first embodiment;

FIG. 7 is a bottom plan view of the first embodiment;

FIG. 8 is an enlarged view taken from FIG. 7;

FIG. 9 is a front perspective view of the fencing panel sheet showing my new design according to a second embodiment; FIG. 10 is a front elevational view of the second embodiment;

FIG. 11 is a rear elevational view of the second embodiment; FIG. 12 is a right side elevational view of the second embodiment;

FIG. 13 is a left side elevational view of the second embodiment;

FIG. 14 is a top plan view of the second embodiment;

FIG. 15 is a bottom plan view of the second embodiment; and,

FIG. 16 is an enlarged view of taken from FIG. 15.

The drawings contain a symbolic break. The portion between the break lines forms no part of the claimed design. The Broken line rectangles in FIGS. 7, 8, 15 and 16 depict the limits of the enlarged view and form no part of the claimed design.

1 Claim, 12 Drawing Sheets
